UNITED STATES PATENT OFFICE.

MARIUS C. KRARUP, OF NEW YORK, N. Y.

REBOUND-CHECK.

1,258,021.

Specification of Letters Patent. Patented Mar. 5, 1918.

Application filed January 29, 1914. Serial No. 815,105.

To all whom it may concern:

Be it known that I, MARIUS C. KRARUP, a citizen of the United States of America, and a resident of New York, county and State 5 of New York, have invented certain new and useful Improvements in Rebound-Checks, of which the following is a specification, reference being had to the accompanying drawings, forming a part thereof.

10 My invention relates to improvements in rebound checks such as are employed in combination with springs, as, for example, such as are used as shock-absorbers in combination with the springs of a vehicle, and its 15 object is to provide a simple and efficient device which will not interfere with the desired action of the springs, but which will effectively prevent undesirable rebound actions.

This and other objects of this invention 20 will appear in the following specification in which I will describe various mechanisms which embody the invention, the novel features of which I will set forth in the appended claims.

25 Referring to the drawings:

Figure 1 is a side elevation of a portion 30 of the frame of a vehicle, its axle which is shown in cross-section, an interposed spring, and a device which embodies the present invention connected with the vehicle frame and the axle.

Fig. 2 is a sectional side elevation of the rebound check device of Fig. 1 drawn on a larger scale, and Fig. 3 is a sectional plan 35 view of the same device. The section of Fig. 2 is taken on the line 2—2 of Fig. 3, and the section of Fig. 3 is taken on the line 3—3 of Fig. 2.

Fig. 4 is a side elevation of another mechanism with its cover removed, which mechanism is also made according to this invention.

In Fig. 5 another modification of structure which embodies my invention is shown 45 in side elevation. The cover of this device is also removed so that its parts may be more readily seen.

Fig. 6 is an end view of a part of a vehicle 50 showing a portion of its axle, a part of the vehicle frame in section with a rebound check which embodies my invention shown in sectional elevation.

Fig. 7 is an inverted sectional plan view 55 of the device shown in Fig. 6, the section being taken on the line 7—7 of Fig. 6 looking in the direction of the arrows.

In Figs. 8 and 9 I have shown two other sectional plan views of the same device; the section in Fig. 8 being taken on the line 8—8, and the section in Fig. 9 being taken 60 on the line 9—9, both of Fig. 6 and in each case looking in the direction of the arrows applied to these respective lines.

Like characters of reference designate corresponding parts in all the figures. 65

10 designates the frame of a vehicle and 11 one of its axles. Between these two parts is a spring 12 which is connected in some suitable manner with both of them.

The device shown in Figs. 1, 2 and 3, comprises a circular casing the base of which is designated by 20. From this base near its periphery extends an annular flange 21 and a shorter inner flange 22. Fitted between the flanges is a vane 23 from which extends 75 a ring 24 which fits loosely around the inner flange 22. The corner of this vane is cut away to provide an opening 25 or, if desired, a hole 25^a may be drilled through it and it is adapted to rest by gravity against a stop 80 piece 26 which is affixed to the flange 21 upon its inner surface. The relation of this stop piece to the flange upon which it is mounted is resilient as by a springy support, so as to moderate the abruptness of 85 the check.

Within the casing is an oscillatory member 30 the hub of which comprises an inner portion 31 which fits both within and without the flange 22, and an outer portion 32 90 which projects outside of the casing and to which an arm 33 is rigidly affixed and held in place by a bolt 34. The member 30 is constructed to form a vane 35. 36 is a cover which completes the casing. This cover fits 95 over the flange 21 and is provided with a central opening through which a circular part of the hub 32 projects. Between the cover and the member 30 are packing rings 37. The cover has a rim flange 38 and bolts 100 or screws 39 fasten it and the casing base 20 together. Some of these bolts pass into the vehicle frame and serve to affix the relatively stationary casing of the device to the vehicle frame.

The outer end of the arm 33 is connected with the axle 11 by some suitable mechanism such for example as by a right and left hand threaded rod 13, the lower end of which screws into a shackle 14 which is affixed to 110 the axle by a ball and socket device and the upper end of which screws into a socket 15

which receives and holds an enlarged head on the end of the arm 34. Such a connection affords ready means for adjusting the distance between the axle and the outer end 5 of the arm 34.

Before describing in detail the mechanisms shown in the other figures of the drawings, I will point out the operation of the device shown in these first three figures.

10 Within the casing is an annular space which is preferably filled with oil. This space is divided into two chambers by the vanes 23 and 35. We will assume that the load on the vehicle has compressed the 15 spring 12 to the degree shown and that the parts are so adjusted that they assume the relative positions in which they are shown in Figs. 1 and 2. Any shock or jar which will further compress the spring will force 20 the end of arm 33 upward and in so doing will move the vane 35 through an arc to the right. This will impart a circular movement to the fluid which will move the vane 23 through an arc almost as great as the arc of 25 movement of the vane 35.

Now it may be seen that when the shock or jar which has been cushioned or taken up by the compression of the spring, has been removed, the spring is perfectly free to 30 turn to its initial or load sustaining position for the reason that there is nothing to prevent the vanes 35 and 23 from moving back to the positions from which they started. It may be seen also that any tendency 35 which the spring may have of itself or aided by external influences to rebound or pass below the point from which it started, will be checked or retarded because at or slightly before rebounding would begin the vane 23 40 has reached its starting point, the stop 26. As it can move no farther except against a strong spring resistance if the stop is resiliant, it arrests the free circulation of oil and therefore effectively checks and retards 45 further movement of the vane 35 to the left and of the arm 33 in a downward direction. The amount of this retarding effect is of course dependent upon the fit of the parts, the size of the hole 25, and the consistency 50 of the oil,—all factors which can be changed to suit existing conditions.

The spring may return therefore quickly to its load bearing position where it is ready at once to cushion another shock. It is to be 55 noted that slow changes of pressure such as changes in the load on the vehicle will not affect the operation of the device as the vane 23, returns when not under pressure from rapid movements of the fluid by gravity to 60 its rest position, the opening 25 allowing for the circulation of the fluid at a limited rate. This opening may be in the vane 35, if preferred. The shape and dimensions of this 65 opening are so arranged that the retarding effect will begin at a point slightly before

the vane has returned to its initial position. Of course this lag and lead of the vane 23 relative to the movement of the vane 35 may be increased by making the opening 25 or hole 25^a larger, or, if desired, a spring may 70 supplement or take the place of gravitation for effecting the return movement of the vane 23. Above the casing is an opening by which it may be filled with oil and if a certain amount of air space is left in it this 75 will have a cushioning effect.

In the structure illustrated in Fig. 4, the casing 40 is of a different shape. The arm 34^a is pivoted at 41 and so connected with the vehicle shaft and the vehicle frame as 80 to move a vane 42 to the right when the vehicle spring is compressed. This vane swings over a concentric surface 43 and draws oil or other fluid out of a chamber 44 through a channel 45 into a chamber 46. 85 In the chamber 44 is a curved surface 47 over which moves the end of a freely pivoted vane 48 which is provided with an orifice 49. This vane in its initial position rests by gravity against an abutment 50 formed in 90 the casing. The edges of the vanes 42 and 48 as in the other structure fit loosely against the casing and its cover.

The operation of this device is similar to that of the other arrangement which has 95 been described fully, but this structure has the advantage of simplicity of form and construction and of small vertical dimensions for a given power of action. Provision is made for filling the device with 100 oil through an opening into an upper chamber 52 from which it runs down into the other chambers through channels 53 and 54.

60 designates the casing of the arrangement shown in Fig. 5. In this case the arm 34^b is raised when the vehicle spring is compressed. This arm is connected at 61 with a rotary pivot to which is also connected within the casing an arm 62. 63 is a vane which is pivoted at 64 and is connected by 110 a link 65 with the arm 62. This vane is arranged to swing over a concentric surface 66.

In the casing is a curved portion 67 over which swings a pivoted vane 68 which, as in the other cases, is provided with an orifice 115 69, and is arranged to rest upon an abutment which checks its movement in one direction.

The operation of this device is similar to that of the others which have been described and this structure has the advantage of having the pivot 61 which passes through the casing above the pivots of the vanes and outside of the pressure chamber.

The remaining figures of the drawings illustrate a simple and possibly a preferred 125 structure. In these figures, 70 designates a cylindrical dash-pot in which is a longitudinally movable piston 71. This piston is mounted on the lower end of a hollow rod 72. The dash-pot cylinder is connected by 130

means of a yoke 73 with the frame 10 of the vehicle. The hollow rod 72 is connected by a bracket 74 with the axle 11 of the vehicle.

5 Below the piston 71 is an auxiliary piston 75 which is affixed to a slotted stem 76 which fits loosely within the lower end of the hollow rod 72.

This structure is filled with oil or other fluid and its operation is as follows: When the vehicle springs are compressed to move the axle 11 toward the frame 10, the piston 71 will be raised thereby, causing the oil or other fluid to be forced out through ports 77 near the upper part of the structure, down through channels 78, and through ports 79 into the lower part of the structure. The suction caused by the upward movement of the piston and also the circulation of oil into the lower part of the cylinder below the auxiliary piston 75, will cause the latter to follow up after the piston 71. Since however, as the spring causes the axle to travel away from the vehicle frame again, 25 the two pistons 71 and 75 will move downward freely without retarding the action of the spring until the auxiliary piston 71 reaches the lower end of its travel and rests upon the head of the cylinder. This will 30 then stop further circulation of the fluid through the channels or passages 78 so that after the piston 71 has reached its initial position, its further downward movement will be checked and retarded by the fluid 35 which is between it and the piston 75. The piston 71 is provided with a pair of openings, the size and arrangement of which will adjust the amount of retarding effect.

The result of this will be obviously that 40 the spring will be allowed to resume its initial position but any tendency of it to rebound beyond its initial position will be checked.

The oil openings through the piston and 45 the means for adjusting their relative positions are shown in Figs. 6, 8 and 9. In the piston are two diametrically opposed openings 80 and a plurality of threaded holes 81, the latter being arranged on the common arc 50 of a circle. Adjustably affixed to the bottom of the piston is a disk 82 in the edge of which are oppositely disposed openings 83 and through which are two screw holes 84. By this arrangement the disk 82 may be attached to the bottom of the piston 71 in such 55 a position that the openings 83 are in alignment with the holes 80, or are ninety degrees out of alignment or are in intermediate positions. By this means the path of flow of the oil may be direct or may be made more or 60 less tortuous to thereby adjust the resistance to its flow and its retarding effect. 85—86 are two disks which carry between them a packing and which surround the hollow rod 65 72. A compression spring 87 is interposed

between these disks and the top of the piston 71. This arrangement is such that if an extreme upward movement is imparted to the piston the disks 86 will strike against the top 88 of the cylinder and the shock will be taken up by the spring 87. When such an extreme movement does occur the upwardly extending annular flange of the piston will cover the ports 77 so that the oil entrapped above the piston will also serve to take up this shock. I have illustrated and described several different structures which embody this invention, for the purpose of showing that it is not limited to any particular construction or arrangement of parts. In fact, I intend that only such limitations be imposed as are indicated in the appended claims.

What I claim is:

1. A rebound check comprising a fluid-containing casing, a positively actuated member, a detached movable member in said casing, and a stop for restraining the detached member against movement in one direction from a predetermined initial position, said detached movable member being arranged to move from and back to its initial position with corresponding movements of the positively actuated member and to engage the stop and retard further movement of the positively actuated member in the direction of its return movement.

2. A rebound check comprising a fluid-containing casing, a positively actuated movable member in said casing, a detached movable member constituting a partial barrier and arranged to be freely moved from and to an initial position by said positively actuated member through the tendency of said fluid, and means for limiting the return movement of said detached movable member to cause the fluid to check further movement of the positively actuated member in a like direction.

3. A rebound check comprising a fluid-containing casing having an endless fluid passage, a positively actuated movable member in said passage, a detached movable member also in the passage, means for moving said positively actuated member in opposite directions to circulate the fluid to thereby cause the freely movable member to move from and back to its initial position with corresponding movements of the positively actuated member, and means for stopping the return movement of the freely movable member at its initial position, to check the circulation of the fluid to thereby check further movement of the positively actuated member in a like direction.

4. A rebound check comprising a fluid containing cylinder, a piston therein, a by-pass around the piston, and a freely movable device arranged to move from and back to its initial position with corresponding move-

ments of the piston and to obstruct said bypass when it has returned to its initial position.

5. A rebound check comprising a cylinder containing oil, an oil passage and ports connecting the passage with the end portions of the cylinder, a positively actuated main piston in said cylinder, and a freely movable auxiliary piston at one side of said main piston arranged to move from and back to its initial position with corresponding movements of the main piston, and to obstruct the flow of oil through said passage in one direction when it is in its initial position.

15 6. A rebound check comprising a cylinder containing oil, an oil passage and ports connecting the passage with the upper and lower portions of the cylinder, a positively actuated main piston in said cylinder, and a 20 freely movable auxiliary piston below said main piston arranged to be moved up and down by the circulation of the oil with corresponding movements of the main piston, and to obstruct the circulation of the oil in 25 one direction when it is in its lower position.

7. A rebound check comprising a cylinder containing oil, an oil passage and ports connecting the passage with the upper and 30 lower portions of the cylinder, a positively actuated main piston in said cylinder, and a freely movable auxiliary piston below said main piston arranged to be moved up and down by the circulation of the oil with corresponding movements of the main piston, and to obstruct the circulation of the oil in 35 one direction when it is in its lower position, said main piston being provided with an opening therethrough.

40 8. A rebound check comprising a cylinder containing oil having an upper cylinder head, an oil passage and ports connecting the passage with the upper and lower portions of the cylinder, a positively actuated 45 main piston in said cylinder, and a freely movable auxiliary piston below said main piston arranged to be moved up and down by the circulation of the oil with corresponding movements of the main piston, and 50 to arrest the circulation of the oil in one direction when it is in its lower position, a buffer spring between the main piston and the upper cylinder head, said main piston being constructed with oil openings there- 55 through and means for adjusting the relative positions of said openings.

9. A rebound check comprising a cylinder containing oil having an upper cylinder head, an oil passage and ports connecting 60 the passage with the upper and lower portions of the cylinder, a positively actuated main piston in said cylinder, and a freely movable auxiliary piston below said main piston and above the ports in the lower portion 65 of the cylinder arranged to be moved

up and down by the circulation of the oil with corresponding movements of the main piston, and to arrest the circulation of the oil in one direction when it is in its lower position, a buffer spring between the main 70 piston and the upper cylinder head, said main piston being arranged to close the ports near the upper end of the cylinder as it approaches the upper end of its path of travel and being constructed with oil openings, and means for adjusting the relative 75 positions of said openings.

10. A rebound check for a pair of resiliently connected bodies, comprising a fluid-containing casing connected to one of the 80 bodies and having an endless fluid passage, a member in said passage connected to be actuated by the other body, a detached member also in said passage movable in both directions with the aforesaid member, and 85 means for arresting the movement of the detached movable member in one direction.

11. A rebound check for resiliently connected members comprising a fluid-containing casing having an endless fluid passage, 90 a piston in the passage adapted to be positively actuated by relative movements of the resiliently connected members, a detached piston movable in both directions with said positively actuated piston and adapted to 95 occupy a fixed initial position and constituting a partial barrier in the passage, and means for restraining the movement of the detached piston in its direction of movement from its initial position. 100

12. A rebound check for two resiliently connected bodies, a fluid containing casing secured to one of said bodies, a piston freely movable from and back to an initial position within said casing, another piston within said casing, adapted to be actuated by relative movements between said resiliently connected bodies and to impart movement to said freely movable piston through the intermedium of the fluid within the casing, and means for checking a return movement of said freely movable piston beyond its initial position. 105

13. A rebound check for two resiliently connected bodies, comprising a casing secured to one of said bodies, a fluid within said casing, a piston freely movable from and back to an initial position within said casing, a second piston within said casing adapted to be mechanically moved by relative movement of said resiliently connected bodies, and to impart a movement to said freely movable piston through the intermedium of said fluid, a projection within 115 said casing arranged to prevent said freely movable piston from return movement beyond its initial position, and through the intermedium of said fluid to thereby obstruct a return movement of said second piston beyond its initial position. 120

14. A rebound check for two resiliently connected bodies, comprising a fluid-containing casing secured to one of said bodies, a piston freely movable from and back to an initial position within said casing, a second piston within said casing adapted to be mechanically moved by relative movement of said resiliently connected bodies, and to impart a movement to said freely movable piston through the intermedium of said fluid, a projection within 125 said casing arranged to prevent said freely movable piston from return movement beyond its initial position, and through the intermedium of said fluid to thereby obstruct a return movement of said second piston beyond its initial position.

14. A rebound check for a vehicle having an axle and a body resiliently supported thereby, said check comprising a fluid containing casing secured to the body, a piston freely movable from and back to a fixed initial position within said casing, another piston within said casing arranged to be actuated by relative movements between said body and axle and to impart movement to said freely movable piston through the intermediation of the fluid within the casing, and means for checking a return movement of said freely movable piston beyond its initial position.

15. A rebound check for a vehicle having a wheel axle and a body resiliently supported thereon, said check comprising a fluid containing casing secured to the body, a piston freely movable from and back to a fixed initial position within said casing, another piston within said casing adapted to be moved from and back to a variable initial position, dependent upon the static load on the body, by relative movements between the body and axle, and to impart movement to said freely movable piston through the intermediation of the fluid within the casing, and means for checking a return movement of said freely movable piston beyond its initial position.

16. A rebound check for spring-mounted

vehicle bodies comprising a fluid-containing casing, a piston therein positively-actuated by relative movements between the body and the axle of the vehicle and adapted to occupy a variable initial position dependent upon the vehicle load, and a detached piston within the casing for strongly retarding a rebound expansion of the spring without offering resistance to a movement of the positively actuated piston from and back to its initial position.

17. A rebound check for spring-mounted vehicle bodies comprising a fluid-containing casing having an endless fluid passage, a piston therein positively actuated by relative movements between the body and axle of the vehicle and adapted to occupy a variable initial position dependent upon the vehicle load, and a detached piston in the passage movable in both directions with said positively actuated piston adapted to occupy a fixed initial position and constituting a partial barrier for retarding the movement of fluid in the passage in one direction.

In witness whereof, I have hereunto set my hand this 22 day of January, 1914, in the presence of two subscribing witnesses.

MARIUS C. KRARUP.
